(57) CLAIM

The ornamental design for a vending kiosk, as shown and described.

DESCRIPTION

FIG. 1 is a front, left side perspective view of a third embodiment of the vending kiosk.

FIG. 2 is a front view thereof.

FIG. 3 is a left side view thereof, the right side thereof being a mirror image; and,

FIG. 4 is a top view thereof.

The broken lines indicate unclaimed portions and form no part of the claimed design. The bottom and rear surfaces do not form part of the claimed design.
